UNITED STATES PATENT OFFICE.

ULA L. COURSON, OF HAHIRA, GEORGIA.

COMBINED LAMP-BASE AND MATCH-SAFE.

1,249,903.

Specification of Letters Patent. Patented Dec. 11, 1917.

Application filed February 21, 1917. Serial No. 150,116.

To all whom it may concern:

Be it known that I, ULA L. COURSON, a citizen of the United States, residing at Hahira, in the county of Lowndes, State 5 of Georgia, have invented new and useful Combined Lamp-Bases and Match-Safes; and I do hereby declare the following to be a full, clear, and exact description of the invention, such as will enable others skilled 10 in the art to which it appertains to make and use the same.

This invention effects the combination of a lamp base and match safe.

Its principal object is to provide, as a 15 part of the lamp base, a compartment wherein matches can be kept, so that they will always be handy for lighting the lamp.

A second object of the invention is to provide in addition to the cover for the match 20 compartment, a keeper for the contained matches so that they may not be spilled when the lamp is being carried. The keeper is designed, however, to permit the removal of the matches separately.

25 A third object of the invention is to keep the matches dry and in good shape for striking at all times even during rainy and foggy weather.

A fourth object is to keep rats from getting matches and thereby eliminate much danger of destructive fires.

A roughened or grit place may be made on or near the lid or cover to strike matches on. These lamps may be made in one continuous piece, that is, the base, the stem and the bowl may be molded in one piece or made in separate pieces and fastened together by taps or cement.

The same numerals of reference designate 40 the same parts throughout the several figures of the drawings, wherein,

Figure 1 is a perspective view of the invention.

Fig. 2 is a top plan view of the same, 45 showing the cover down, whereas in Fig. 1 it was raised.

Fig. 3 is a section on line 3—3 of Fig. 2.

Fig. 4 is a perspective view of the keeper 50 that is inserted in the top of the compartment to contain the matches.

The numeral 1 designates a lamp base that may be made out of wood, metal or any suitable material. This base is recessed to 55 form the compartment 2, and has a tapped hole 3 at its center in which the remaining

lamp structure is secured. A cover 4 is provided for the compartment 2, and this cover has a pivotal mounting on the studs 5, one each being inserted in the end wall of the recess portion 6 of the lamp base. 60 The cover 4 has a strip 7 at the center of one of its longitudinal edges, and the bending of this strip around the pins 5 provides the pivotal connection previously referred to. A strip 8 integral with the other longitudinal edge of the cover 4 is turned over to form a cylindrical finger-lifter for the cover. 65

The keeper previously referred to is composed of a longitudinal piece 9, the two triangular end pieces 10 and the end plates 11. 70 The parts 9, 10 and 11 are all integral parts of the keeper which is designed for insertion at the top of the compartment 2, the back and end walls of the compartment 75 being so cut away that it will leave the piece 9 and the end pieces 10 of the keeper flush with the walls of the rest of the compartment when the keeper is in position. The keeper is designed to fit in its position in 80 the compartment 2 to prevent its displacement by jarring but not so snugly as to preclude its removal for the filling of the compartment.

When in use, the compartment 2 is intended to be filled with matches, and matches may be withdrawn separately therefrom (after the cover 4 has been raised) by removing them between the ends of the end plates 11 and the front wall of 90 the compartment 2. Since the space between the front wall of 2 and the ends of the plates 11 is too small to permit the removal of more than two matches at the same time, it will be seen that the matches 95 contained in 2 cannot be easily spilled, such as would be the case were the keeper not provided.

By removing the keeper the compartment 2 may be easily refilled when empty after 100 which the keeper may be replaced.

What is claimed is:

In a combination lamp-base and match-safe, a lamp-base having a compartment formed therein, a cover pivotally connected 105 with the lamp-base and adapted to cover the compartment, said pivotal connection comprising a recess formed in the lamp-base adjacent the back edge of the compartment, pins inserted in the end walls of said recess, 110

and a projection on the cover engaging the pins in surrounding relation, a projection on the cover so turned as to provide a finger lift, and a removable keeper to prevent the spilling of matches, said keeper being adapted for frictional engagement with the walls of said compartment and comprising a rectangular longitudinal piece, triangular end-pieces and end-plates relatively shorter than

the end-pieces so as to permit the removal of matches singly or in pairs.

In testimony whereof I have signed my name to this specification in the presence of two subscribing witnesses.

ULA L. COURSON.
